(57) **CLAIM**

The ornamental design for a combined selfie stick with fill light as shown and described.

DESCRIPTION

FIG. 1 is a front, right and top perspective view of a combined selfie stick with fill light, showing my new design. FIG. 2 is a front, right and top perspective view of a fill light of the combined selfie stick with fill light of FIG. 1. FIG. 3 is a rear, left and bottom perspective view of the fill light of FIG. 2.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is an enlarged view of detail 10 in FIG. 3.

FIG. 11 is a front, right and top perspective view of a selfie stick of the combined selfie stick with fill light of FIG. 1. FIG. 12 is a rear, left and bottom perspective view of the selfie stick of FIG. 12.

FIG. 13 is a front elevation view thereof.

FIG. 14 is a rear elevation view thereof.

FIG. 15 is a left side elevation thereof.

FIG. 16 is a right side elevation view thereof.

FIG. 17 is a top plan view thereof.

FIG. 18 is a bottom plan view thereof.

FIG. 19 is an enlarged view of detail 19 in FIG. 11.

FIG. 20 is an enlarged view of detail 20 in FIG. 11; and, FIG. 21 is an enlarged view of detail 21 in FIG. 12.

The dashed broken lines depict portions of the combined selfie stick with fill light that form no part of the claimed design. The dot-dash broken lines in FIGS. 3, 10-12, and 19-21 depict the boundaries of the enlargements and form no part of the claimed design.

1 Claim, 21 Drawing Sheets
